UNITED STATES PATENT OFFICE

THOMAS G. HOWES THOMAS, OF BRISTOL, ENGLAND

BLOTTING APPLIANCE

Application filed May 19, 1924, Serial No. 714,464, and in Great Britain April 9, 1923.

The invention relates chiefly to improvements in blotting rollers to be used with fountain pens. The main object being to provide an efficient means at the sides of the 5 rollers to prevent unwinding when in use, hereafter referred to in detail, such means allowing strips to be easily torn off, leaving the clean under layer free from projections.

The complete invention is a blotting roller 10 contained in an attachment fixed to fountain pens or made with any such pen, cover or case, or made separately as a roll blotter for use without being attached to any fountain pen. The blotting roller, which has its ends partially or wholly adhesively fixed and colored 15 revolves on a pin, between arms attached to a frame fixed or screwed to any pen in any suitable position for use as a blotter, either on the pen cap or body of the pen itself.

20 I attain all these objects in various ways and the preferred manner of carrying out the invention is shown by Figures 1 to 6 inclusive details of which are set forth in the following description and claims.

25 Figure 1 is a vertical section on line 1—1 of Figure 2.

Figure 2 is an end elevation of Figure 1.

Figures 3 and 4 are elevations at right angles to each other.

30 Figure 5 is a section on line 5—5 of Figure 3.

Figure 6 is a section on line 6—6 of Figure 4.

The blotting rollers or refills are made of 35 blotting paper, as shown by 1 in Figure 1, or other absorbent material. This material may be white or any variation of color made from a long strip rolled on a center core, as shown by 2 in Figure 1, fixed for tearing off easily any layer or circular portion that has become saturated or useless. The preferred method of securing is made by surfacing the outside of the rollers at the ends, either over the whole surface or in lines or 45 designs as shown by 3 in Figures 1 and 2; with a layer of adhesive. Such surfacing may be painted in color, or color can be mixed with adhesive.

The blotting rollers are made with a center 50 hole in the core slightly larger than the car-

rying pin. This core may be made of hard material or manufactured substances.

Such cores may be made separately and rolls wound on them, or made with the blotting material wound the same time as the 55 cores.

Having described the blotting rollers and the method of making same, I now describe the preferred manner of using such blotting rollers.

Figure 3 shows the pen cap "h," the penholder "j," and the nib "k," of a fountain pen with the roll blotter (the term used for a blotting roller attached to a frame) fixed correctly for writing purposes. The attachment 60 shown is a circular frame "a," fixed to the pen cap "h," with a fixed arm "e" and pin "f" on which the roller "g" revolves, and a swivel arm "d." This arm "d" is swivelled on a rivet or pivot slotted at top to take the 65 end of pin "f." The lower end has a nib projection "i" on the inside which slides into a recess in "a." A slight groove is made on the side of "a" following the movement of 70 lower end of swivel arm which allows it to be raised or lowered, to place a blotting roller 75 on the pin.

To prevent the pen cap "h" from being pushed through "a" and so impede the roller's movement, a top plate "b" is cut out as shown 80 in Figure 6, the outside edge being cut square to form shoulders for the cap "c" to fix tightly over. To open the swivel, one edge of the top plate "b" is cut at "v" sufficiently to allow 85 it to pass.

The cap "c" is grooved on two sides to pass over the arms. Figure 4 is a side elevation of Figure 3, showing in broken lines how the swivel arm is lowered and raised to place 90 a roller on the pin.

Having thus fully described my invention what I claim as new and desire to secure by Letters Patent is:—

1. A pen attached blotter comprising two 95 arms mounted at the end of a pen and a blotter roller pivotally mounted therebetween, strips of blotting paper wound on the roller, adhesive strips applied to the edges of the paper to hold the roller together and allow soiled pieces of paper to be torn off.

2. The structure as set forth in claim 1 in which one of the blotting holding arms is swivelly mounted on the pen and has a slot at the other end for mounting one end of the roller, so that the latter may be readily removed, all as described, and shown on the accompanying drawings.

Dated this 6th day of March, 1924.

T. G. HOWES THOMAS.
